RAIL FASTENING DEVICE

Filed Feb. 27, 1929

UNITED STATES PATENT OFFICE

LLOYD C. LIKENS AND THOMAS J. DAVIS, OF GALESBURG, ILLINOIS

RAIL-FASTENING DEVICE

Application filed February 27, 1929. Serial No. 343,134.

Our invention pertains to ties and fasteners for railway rails and it contemplates the provision of a simple and inexpensive device through the medium of which low joints will be retained in proper position and the spikes will be prevented from pulling from the joint.

The invention further contemplates the provision of railway joints so constructed and arranged that the joint will remain level with the consequent prevention of injury to the rails at the joints.

Other objects and advantageous features of the invention will be fully understood from the following description and claims when the same are read in connection with the drawings accompanying and forming part of this specification, in which:

Figure 1 is a perspective view of the joint of two rails of our novel fastening means.

Figure 2 is a similar view of our novel bed plate.

Figure 3 is a sectional view illustrating our novel construction.

Similar numerals of reference designate corresponding parts in all the views of the drawings.

We illustrate ties 1 and the usual rails 2. Adapted to rest beneath the base 3 of the rails is a bed plate 4 having the kerfs 5, the round apertures 6 and the square apertures 7. This plate 4 is adapted to rest preferably on and extend the distance of three complete ties although they may be made longer or shorter in the discretion of the manufacturer. The plate is also positioned so that the bases 3 of adjoining rails rest thereon and the said plate is secured to the ties 1 by means of spikes 8 that pass through and rest in the kerfs 5 of said plate. After the plate has been secured to the ties the rail is positioned thereon and fish plates 9 are placed so as to engage the base and web of the rails. At this point we would have it distinctly understood that the fish plates are bent downwardly at an angle at the point of contact with the bed plate 4 so as to receive and securely hold the flanged portion of the base 3 of the rails 2 whereby creeping endwise or transversely is materially precluded. Bolts 10 secure the fish-plates, base portions 3 and bed plate 4 to each other

and the said bolts pass through the round openings 6 in the bed plate 4.

The fish plates are secured to the web of the rails and to each other by means of the bolts 11 while the fish-plates are further secured to the bed plate and to the ties by means of the bolts 12 that pass through the square apertures 7 of the bed plate 4.

It will be gathered from the foregoing that the novel construction of bed plate will keep the rails even at all times at the joints and will manifestly prevent the spikes from pulling from the joint. The spikes cannot be pulled from the ties by the rails working up and down because this movement of the rails is precluded; all uneven joints and lifts are prevented from accumulating and elimination of broken rails at joints is effected; it being a well known fact that generally rails break at the joints.

The construction of our device provides for the elimination of noise and vibration at the joint and because the rails are secured rigidly to each other and to the ties rocking of the cars when crossing joints is prevented and consequently pulling of the spikes due to rocking is eliminated.

It will be further understood that the device is extremely simple in construction and inexpensive to produce and will require no skilled labor either in its production or attachment and it assures constant level of the rails at the points.

What we claim is:

1. The combination of ties, a bed plate having apertures formed therein whereby fastenings may be employed to secure the plate to the ties; said plate being further adapted to be provided with apertures for the reception of bolts, rails adapted to rest on the bed plate, fish-plates adapted to be secured to the rails and having angular portions to engage one wall of the base of the rails, means for securing the fish-plates to the bed plate and ties and means for securing the fish-plates, rails and bed plate to each other.

2. The combination of ties, a bed plate adapted to bear on the ties, a rail positioned on the plate, fish-plates adapted to bear against the rail and having an angular por-

tion that co-acts with the bed plate to surround the web and base of the rail, means for securing the fish-plates to the rail, other means for securing the fish-plates to the bed plate and means for securing the rail, fish-plates and bed plate to each other; said bed plate being so constructed and arranged that fastening means may enter the bed plate so as to secure said plate to the ties.

5 10 In testimony whereof we have hereunto set our hands.

LLOYD C. LIKENS.
THOMAS J. DAVIS.
